UNITED STATES PATENT OFFICE.

ALEXANDER DICKEY, OF BAKERSFIELD, CALIFORNIA.

SOCKET WRENCH.

Application filed February 25, 1924. Serial No. 695,042.

This invention relates to socket wrenches or the like, and aims to provide novel means whereby wrench socket members may be readily and easily inserted and removed from the wrench supporting the same, thereby adapting a single wrench for use in connection with wrench sockets of various sizes.

Another important object of the invention is to provide means for locking the wrench sockets within the wrench against accidental displacement, the locking means being such as will operate to release, under a pull directed thereto, longitudinally of the wrench proper.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a side elevational view of a removable wrench socket, constructed in accordance with the invention.

Figure 2 is a top plan view thereof.

Figure 3 is an elevational view of the removable socket wrench, the removable socket being shown in section.

Referring to the drawing in detail, the reference character 5 designates the wrench proper, which may be formed of the usual construction, the same being provided with a socket 6 so constructed that it will receive the hexagonal section 7 of the socket member associated therewith.

The socket member is preferably hollow and accommodates a spring arm 8 that has

one end thereof secured to the wall of the hollow portion, at 9, the opposite end of the spring arm carrying a finger 10.

The finger 10 has a rounded outer extremity and is designed to engage the shoulder 11 formed within the socket 6, the finger 10 being shown as passing through a lateral opening formed in the socket member.

It is to be understood that the sockets employed in connection with the wrench, have not receiving openings of various sizes and construction adapting the wrench for use in connection with practically any size nut, by merely removing and inserting the proper sized socket member in the wrench.

When it is desired to remove a wrench socket, it is only necessary to pull the same longitudinally of the wrench supporting the same, to the end that the finger 10 will ride over the shoulder, removing the spring arm and releasing the wrench socket member, whereupon another wrench socket may be readily inserted, the spring arm acting to automatically move the finger to its active position.

I claim:

In a wrench, a socket having an internal shoulder, a removable socket having an extension formed with a bore and having an opening in one wall thereof, said extension being fitted in the first mentioned socket, a spring arm secured within the bore at one side, and adjacent to one end of the bore, said spring arm extending across the bore, a pin on the opposite end of the spring arm and extending through the opening in the socket, to engage the shoulder of the first mentioned socket.

In testimony that I claim the foregoing as my own, I have hereto affixed my signature.

ALEXANDER DICKEY.
